UNITED STATES PATENT OFFICE.

AARON G. DYER AND JAMES M. DYER, OF SAN FRANCISCO, CALIFORNIA.

ROCK-CRUSHER.

SPECIFICATION forming part of Letters Patent No. 310,656, dated January 13, 1885.

Application filed December 26, 1883. (No model.)

To all whom it may concern:

Be it known that we, AARON G. DYER and JAMES M. DYER, of the city and county of San Francisco, and State of California, have 5 invented Improvements in Rock-Crushers; and we hereby declare the following to be a full, clear, and exact description thereof.

Our invention relates to certain improvements in apparatus for crushing and pulverizing rock; and it consists in certain combinations and devices, hereinafter described and claimed, and which will be more fully explained by reference to the accompanying drawings, in which—

15 Figure 1 is a vertical section of our apparatus taken through the axis. Fig. 2 is a top section on line xx , Fig. 1, showing the upper part of the inclosing cylinder. Fig. 3 is a horizontal section on line yy , Fig. 1, showing 20 the balls and the die J.

A is a base supporting a journal box, B, through which the lower end of the vertical shaft C extends, and by which it is guided. D is a bevel gear-wheel fitting the shaft, and 25 driven by a pinion, E, upon the horizontal shaft F, to which power may be applied in any suitable manner. A feather, a, is fixed on the shaft C and fitted to a keyway in the wheel D, so that the shaft may have a vertical movement to correspond with that of the cone above without interfering with the action of the gearing. The shaft C extends up through a stationary conical base, G, suitably supported upon a fixed frame-work, and upon 30 the outer periphery of which a grooved annular die, H, rests. The balls I run in the groove or channel in the top of the die H, and a second grooved annular die or shoe, J, of similar shape to the die H, rests upon the tops 35 of the balls and supports the base of the main cone, which rests upon a suitable bearing or hollow section, W, which is supported by lugs or projections v, formed on the lower inner side of the inclined hopper-shaped rim V, the 40 under surface of which bears upon the upper die, J, as shown in Fig. 1. The conical base G serves to throw the material which falls upon it from above outward, so that it passes between the balls and the dies. Around the 45 outside flange of this base, and exterior to the dies, is a screen, L, within which the material is retained as long as may be necessary to

pulverize it. Outside of this is a rim, M, and upon one side is an opening, m, through which the pulverized material is discharged. The 55 flange forming the bottom of the conical base G, and of the pan surrounding it, is inclined so that the discharge side is the lowest, as shown. Upon this flange is an amalgamated copper plate to retain any free gold. The 60 main cone K has a heavy removable shoe, N, upon the top, upon which the crushing takes place, and the shaft C passes up through and is firmly secured to the cone, so that when it is rotated it turns the cone.

When the cone K, carrying the shoe N and supported in the manner above referred to, is rotated by the shaft C, it causes the balls to roll around in and between the grooved dies H and J, thereby thoroughly pulverizing the 70 material which passes between them. Above the cone K is a hollow cylinder formed of sections O, set one upon another until sufficient depth is formed, when they are secured together by bolts P, which pass through lugs or 75 flanges Q upon the outside of the sections, and by nuts R, which screw down upon said bolts. The lower section or sections forming this cylinder have the interior made diverging, or curved outward, so as to approximate in shape 80 the upper part of the cone, or its shoe, the edges approaching those of the cone, so that a gradually-narrowing space is formed from the top to the bottom of the cone. The upper section, O, of the cylinder has arms S, from which 85 a fixed central shaft, T, extends upward, and has a ball or other universal joint, U, at the upper end, which allows the lower end of shaft T to move to one side and out of line with the shaft C as the latter rotates with cone K. 90 When this is done, it will be manifest that one side of the interior of the cylinder will be nearer to the cone K than the other; and ore or rock which is fed in at the top of the cylinder will be wedged between it and the cone at the wider 95 portions. This causes the cylinder to travel around with the cone when the latter is driven, and as the space between the two becomes contracted the rock will be crushed, and will settle down, the operation being repeated until it 100 flows out through the narrow space between the edges of the cone and cylinder. An inclined hopper-shaped rim, V, receives the crushed material at this point and directs it

through an annular space inside the upper annular die, J, so that it falls upon the conical base G, and is directed outward into the channels where the balls travel, as before described.

5 It will be seen that any section of the cylinder can be replaced when worn or broken. The shoe or top of the cone may also be renewed, and the annular dies between which the balls travel, the whole forming a complete 10 crusher and grinder.

Having thus described our invention, what we claim as new, and desire to secure by Letters Patent, is—

15 1. In a crushing apparatus, a cone having a diverging base and a central vertical shaft, in combination with a hollow cylinder surrounding the cone, and having its lower interior section made diverging and approximating the form of the exterior of the cone, and an independent guide-shaft having its upper end journaled out of line with the cone-driving shaft, substantially as herein described.

20 2. In a crushing apparatus, a cone having a diverging base, a central vertical driving-shaft, a hollow cylinder having a diverging conical base, and an independent shaft standing out of line with the cone-driving shaft, in combination with annular grooved dies and the balls upon which the apparatus rests and is rotated, 25 substantially as herein described.

30 3. In a crushing apparatus, a vertical rotating cone, the supporting-balls, the grooved an-

nular dies, a cylinder surrounding and resting upon the cone, and having its lower section diverging and corresponding with the exterior 35 surface of the cone, and an independent guide-shaft for said cylinder, arranged out of line with the cone-shaft, in combination with a guiding chute or hopper, V, by which the material escaping between the cone and the cylinder is delivered between the balls and dies, substantially as herein described.

4. In a crushing apparatus, the cone K, the vertical rotating shaft, the cylinder O, having its lower part shaped similarly to the cone upon 45 which it rests, and a shaft independent of the cone-shaft, extending upward at an angle thereto, in combination with grooved annular dies, intermediate balls, and a conical base, G, substantially as herein described.

5. In a crushing apparatus, the vertical rotating cone K, shaft C, and the superposed cylindrical casing O, in combination with the shaft T, the ball U on said shaft, and the box in which the ball fits, whereby the angle of the 55 shaft may be changed relative to the axis of the cone, substantially as described.

In witness whereof we have hereunto set our hands.

AARON G. DYER.
JAMES M. DYER.
